UNITED STATES PATENT OFFICE.

FRANK E. COOMBS, OF AU SABLE FORKS, NEW YORK.

APPARATUS FOR THE MANUFACTURE OF ACID SULFUROUS PREPARATIONS.

1,147,376.

Specification of Letters Patent.

Patented July 20, 1915.

Application filed April 16, 1912. Serial No. 691,231.

To all whom it may concern:

Be it known that I, FRANK E. COOMBS, a citizen of the United States, residing at Au Sable Forks, in the county of Essex and State of New York, have invented certain new and useful Improvements in Apparatus for the Manufacture of Acid Sulfurous Preparations, of which the following is a specification.

10 This invention relates to the manufacture of acid sulfurous preparations; and it comprises means for burning sulfur to produce sulfurous preparations, said means comprising a valve controlled device for supplying low temperature molten sulfur in regulable amounts, a retort or like means receiving such molten sulfur and means for burning sulfur vapor produced in such retort or like means; all as more fully hereinafter set forth and as claimed.

15 The present invention comprises a simple, cheap and ready means for producing relatively concentrated solutions of sulfurous acid, or of acid sulfites such as the acid sulfite of lime, mixed acid sulfites of lime and magnesia, acid sulfite of soda, etc., and for applying SO_2 in the defecation of cane and beet juice in the manufacture of sugar.

20 The regulable combustion of sulfur offers some difficulty in practice owing to the properties of that element, which forms several allotropic modifications having different physical properties. Rhombic, or ordinary sulfur, melts at about 114° C., to form a thin liquid which flows readily and can be discharged from jet nozzles. As the heat increases however the liquid sulfur changes into another and allotropic viscid form in increasing proportions with the rise of temperature until at about 200° it becomes black and so thick and gummy as to be quite difficult to handle. In using a feed of liquid sulfur it is therefore necessary to work between rather narrow temperature limits, usually between 115° and 130° C. At still higher temperatures it vaporizes freely, boiling finally at about 444° C. There is of course no difficulty in handling the vapor.

25 In the present invention, it is desirable to control the flow or feed of sulfur to the combustion device and to control the combustion within rather narrow limits, and the foregoing principles are therefore utilized.

30 In the present invention, the sulfur to be burnt is supplied to a suitable combustion

device to produce sulfur dioxid and a current of this sulfur dioxid is led into a countercurrent device where it meets a downflowing flow of water, or other liquid, or of water carrying a suitable base. This flow is utilized to form and regulate the draft producing the dioxid current.

35 In the accompanying illustration I have shown, rather diagrammatically, certain means within the present invention.

40 In this showing, Figure 1 is a perspective view with certain elements in section, showing a complete apparatus for making sulfurous acid or acid sulfite solution, or for sulfitation of sugar juices; Fig. 2 is a section showing a sulfur feeding device; Fig. 3 is a section of a combustion chamber for sulfur; Fig. 4 is another view of the same on line $x-x$ of Fig. 3 showing the feeding device 45 assembled with the burner; Fig. 5 is a sectional view of another form of combustion chamber; and Fig. 6 is another section of the same on line $y-y$ of Fig. 5.

45 In the showing of Fig. 1, element 1 represents a sulfur burner and 2 a sulfur feed thereto. The burner delivers sulfur dioxid into conduit 3, valved at 4 and having an extension 5 leading to a stack (not shown) or other means of disposing of waste gas. 50 Below the valve is another communicating conduit 6 leading to absorber 7. Interiorly this absorber may have any usual construction, such as cross-plates (not shown), baffles, etc. The inlet for sulfur dioxid enters the absorber at a low point. At the top, liquid, such as sugar liquor, water, lime water; milk of lime, soda solution, etc., is fed in through pipe 8, fed by pump 9 having steam inlet 10. The bottom of the absorber vessel is tapered to form a jet nozzle 11, surrounded by an injector casing 12. Between this casing and the top of the absorber extends a pipe 13. The outflow of solution from the absorber with this arrangement serves to cause a draft of gas through the absorber. Below the injector casing extends liquor pipe 14, which may have a bend in it to aid in the suction of the downgoing liquid. The end of the liquid pipe extends into reservoir 15, where it is liquid sealed. In this reservoir is located a float 16 having a stem 17 extending upward through guide 18 into engagement with rocker arm 19. This rocker engages cross-bar 20 which at 105 one end controls valve 21 in the steam inlet of the pump supplying liquid to the ab-

55

sorber. Liquid is removed from the reservoir by pump 22 and sent to a place of use through pipe 23. Steam is furnished the pump by steam pipe 24 having a valve 25 controlled by the other end of the cross-bar. The float stem may further actuate through a chain 26, or other suitable connection, the damper or valve (4) in the waste pipe for sulfur dioxid.

10 In Fig. 2 is shown in detail the construction of the sulfur feed (2) for the sulfur burner (1). In this feed device, there is a sulfur casing (marked 2) or hopper for containing sulfur. As shown, this is mounted 15 in casting 27 of the general shape of a funnel, having a downward continuation as pipe 28. At the top it is laterally flanged at 29. Fitting around this casting but spaced away somewhat to form a chamber therebetween is a casing 30 having a corresponding lateral flange 31 at its top. At the bottom it encircles the downward pipe-like continuation of the casting, suitable packing means being employed to make a joint therebetween. 20 Heating liquid may be led into the chamber through 32 and condensate discharged at 33. At the top, the sulfur hopper or casing may be bridged by bar 34 in which is screw-threaded valve rod 35, provided with hand-wheel 36 and extending 25 downward to a cone-shaped valve plug 37 adapted to seat in the stated pipe-like continuation (28) of the casting and close the same. Cross-rod 38 may be provided in the 30 sulfur hopper for supporting the valve rod. It is a useful expedient to surround the valve rod with a protective tubular jacket or casing 39. This sulfur feeding device may be used in connection with the form of 35 sulfur burner shown in Figs. 3 and 4 or that of Figs. 5 and 6.

In Figs. 3 and 4, the burner is constituted by a bottom plate, flanged at 39' and having an upwardly extending wall 40. The bottom slopes toward the center and is provided 45 with a series of transverse ridges 41. Mounted on this bottom is a casing 42 provided with outlet 43 for sulfur dioxid and inlets 44 and 45 for admission of air, these 50 inlets being suitably closed, as by plate 46, for controlling the amount of air admitted. Inlet 47 permits the introduction of molten sulfur from the discharge pipe (28) of the sulfur feeding device. By allowing thinly 55 liquid sulfur to drip down on the bottom or hearth the space between the first pair of ridges can be filled, and then, by overflow, the space between the second, and so on. The area of molten sulfur exposed for combustion 60 can thus be adjusted and thereby the rate of production of sulfur dioxid.

In the structure of Figs. 5 and 6, in lieu of directly delivering the thinly liquid molten sulfur to a burning hearth it is delivered 65 to a volatilizing hearth or retort and sent

into the burner proper as vapor. In this structure, element 48 is a box-like casting having an outlet (43) for sulfur dioxid. At opposite points are two air inlets, 49 and 50 adjustably closed by doors 51, 52. At its top, the casting has a volatilizer element or hearth 53 sloping downwardly toward one end. At the other end it is provided with a channeled downward prolongation 54, the channel being arranged to form a jet nozzle 55. Seated in this prolongation and in open communication with the nozzle is air pipe 56 leading from a suitable source (not shown) of air under pressure. Mounted above this volatilizer element and closing the retort chamber which it forms, is a plate 57 carrying the inlet pipe (28) from the sulfur feed.

In the operation of the present invention, sulfur molten at a temperature at which it is thinly liquid and will flow freely, best 85 around 120° C., is fed down into the sulfur burner from 2. Here it is converted into sulfur dioxid which ascends through pipe 3. If for any reason the apparatus is temporarily out of function as regards using 90 the sulfur dioxid, the gas may be allowed to escape through 5. Normally however the gas passes by 6 into 7 where it is met by downflowing water, sugar liquor, or water and base, according to whether sulfurous 95 acid or an acid sulfite is desired. The saturated solution escapes downward through 11 and pulls residual gas from the absorber through 13, thereby causing a draft through the entire apparatus. As the solution accumulates in 15, the float rises closing the steam inlet to pump 9, thereby stopping the feed of liquid to the absorber and also the draft through the sulfur burner and system generally. At the same time, the waste 100 105 gas outlet damper 4 may be opened to dispose of any residual sulfur dioxid in case the rise is sufficient to stop operation. The rise in the float however tends to open valve 25 allowing steam to go to pump 22 and discharge liquid from the reservoir through 23. As will be perceived, the whole system is governed by the float in the reservoir and is very sensitive to changes in demand for liquor.

In the sulfur feed, the amount of steam led into the heating jacket should be that which will just about melt the sulfur sufficiently to form a thinly liquid product which will feed regularly through 28. Any 110 increase in temperature over about 140° C. will prevent the regular feed necessary in the present invention. The liquid sulfur in the furnace of Fig. 3 is introduced at a rate which will form a pool of the desired area 115 on the hearth, the ridges 41 aiding materially in gaging the exposed area. The amount of sulfur burning per time unit is of course proportional to the surface area. In the furnace of Fig. 6, the thinly liquid 120 125 130

sulfur delivered from 28 runs down to the deepest part of the hearth where it is boiled or volatilized by the heat of the combustion below and the vapors passing out through 5 55 are carried forward by a jet of air from 56, thus forming a flame plume of burning sulfur immediately below the hearth and partly impinging thereon.

What I claim is:—

- 10 1. An apparatus for making preparations containing sulfurous acid comprising a chamber, a sulfur burner in said chamber comprising a retort, means for regulably supplying low-temperature molten sulfur 15 to said retort and a burner nozzle beneath and in open communication with the retort and chamber.
2. An apparatus for making preparations containing sulfurous acid comprising a chamber, a sulfur burner in said chamber comprising a retort, means for regulably supplying low-temperature molten sulfur to 20 said retort, a burner nozzle beneath and in open communication with the retort and chamber and means for supplying a jet of air to said nozzle.
3. In a sulfur burner, means for supplying molten sulfur, a retort chamber communicating with said means, a jet nozzle in 25 open communication with said retort and located to direct a flame jet therebeneath, a

casing inclosing said jet nozzle and provided with means for regulably allowing entrance of air and means for introducing a jet of air into said jet nozzle.

4. In a sulfur burner, a burner casing having an exit for sulfur dioxid and controllable inlets for air, a dished top for said casing having a nozzle mounted on its lower face in open communication with the chamber formed by the dishing, a top plate forming a roof for said chamber, means for introducing molten sulfur into said chamber and means for directing an air current through said nozzle.

5. An apparatus for burning sulfur comprising a chamber, a retort in said chamber, means for supplying molten sulfur attached to said chamber and in communication with said retort, and a jet nozzle in communication with said retort and said chamber and located beneath the retort whereby sulfur may be delivered from said retort into said chamber.

In testimony whereof, I affix my signature in the presence of two subscribing witnesses.
